United States Patent Office

Des. 226,290
Patented Feb. 6, 1973

226,290

CATHETER

Charles H. Cohen and Vernon F. Leonard, Denver, Colo.,
assignors to Goldberg Plastics, Inc., Denver, Colo.

Filed Mar. 15, 1971, Ser. No. 124,648

Term of patent 14 years

Int. Cl. D24—04

U.S. Cl. D83—12

FIG. 1 is a top plan view of the catheter showing our new design, the bottom and side views being mirror images;

FIG. 2 is a rear end view thereof;

FIG. 3 is a front end view thereof;

FIG. 4 is a top plan view thereof with the tip removed, the bottom and side views being mirror images;

FIG. 5 is a top plan view of the removed tip, the bottom and side views being mirror images; and

FIG. 6 is a front end view of the removed tip.

We claim:

The ornamental design for a catheter, as shown and described.
